UNITED STATES PATENT OFFICE.

ALBERT D. THOMAS, OF KEOKUK, IOWA.

BRICK-MACHINE.

SPECIFICATION forming part of Letters Patent No. 315,855, dated April 14, 1885.

Application filed February 17, 1885. (No model.)

To all whom it may concern:

Be it known that I, ALBERT D. THOMAS, a citizen of the United States, residing at Keokuk, in the county of Lee and State of Iowa, have invented certain new and useful Improvements in Brick-Machines, of which the following is a specification, reference being had to the accompanying drawings.

This invention is an improved machine and process for making brick by filling and compressing pulverized clay in molds by plungers which have peculiar motions by which they approach each other from the top and bottom with varied relative motions until the clay is compacted into very hard, dense, and well-united brick, which are then pushed up out of the molds and removed while the molds are again filled for making more brick in a like way.

The invention consists in various new and useful features which are made and used substantially as set forth hereinafter, and as shown in the accompanying drawings, in which—

Figure 1 is a side elevation of machine. Fig. 2 is a like sectional elevation. Fig. 3 is a front elevation. Fig. 4 is a top or plan view. Fig. 5 is a sectional detail of part of mold. Fig. 6 is a detail of friction-clutch. Fig. 7 is a plan detail of mold; and Fig. 8 is a sectional elevation detail of upper plungers.

The machine is made with a bed-plate or frame, A, which rests on wooden sills or otherwise, and with upright frames A' A' A³, to support the operative parts. It has a mold-block, B, and a brace, B', between the frames A' and A², which, with the bed-plate, hold them solid. The frame A' is wide enough to hold the mold-block and several associated parts. The frame A² is made with a front and back portion, as shown in Figs. 1, 2, and 4, the front part corresponding to frame A' and the back part corresponding with frame A³.

The parts which act directly in making the brick are held between and by the corresponding parts of frames A' A², and the motive-power gearing is held between and by the corresponding parts of frames A² and A³. The two portions of frame A² are held together by an abutting splice-joint and bolts above and by the bed-frame below. The frames A' A² A³ are held solidly together by the bed-plate

A below, to which they are bolted. The clay is received by a hopper, C, from an elevator or otherwise, from which it descends into a filler-box, C', which reciprocates upon a table, C², to receive the clay from the hopper above and to feed it to the molds in front and below, and has an apron, C³, extending back, which comes under hopper C when the box C' is moved forward to fill the molds and to push the brick forward from them onto table C². The mold-block B has two or other number of molds, b b, cut vertically through it. The table C² behind and table C⁴ in front abut flush against the top edge of the mold-block, for use in feeding the molds and in discharging the brick.

The table C² is made with hard wood or other slats, c, extending forward, over which the brick are pushed out by the motion of box C'. The spaces between the slats let any loose clay fall through out of the way of the brick. The slats are held by a cross-bar held to frames A' A², and by a cross-bar at the outer ends.

The mold-block B is formed of parts D D, which extend between the two frames A' A², to which they are held by means of horizontal lugs which project from each before and behind on each side, and of cross parts D' D' D³, which fit into parts D D at their ends, and are held by bolts which extend through parts D D and screw into their ends. These parts D D and D' D' D³ inclose the mold-spaces b b between them, which are lined on all sides by hard and polished steel plates d d'. The plates d d' are let into panel-depressions cut into the side walls, with dovetail joints above and below, which are arranged to hold the steel plates solid and secure. The steel plates are mitered together at the corners.

The wear on the molds from the compression of the clay in them is most in the center, and can be made good at any time by replacing the polished steel plates.

The plates d d' and the blocks into which they fit have their surfaces flush with each other and form guideways for the brick. The molds b b have plungers E E, which descend into them accurately from above, and plungers F F, which work up and down in them from below to press the brick and push them up and out and to open the molds. These

plungers are held by plunger-heads E' F', which fit into guideways in frames A' A², which hold them true in place and allow them to move vertically while so held. The upper 5 plunger-head, E', has lugs or parts at its sides which extend upward and hold a heavy pivot bolt or pin, E², which engages link-bar E³ from pitman-lever H to push the upper plungers down to press the brick, and to pull them 10 up to free the molds to admit the discharge of the brick and the refilling of the molds. The lower plunger-head, F', has a heavy pivot pin or shaft, F², which projects through openings in frames A' A², to engage with link-bars F³ 15 from pitman-lever H, to draw the lower plungers up to press the clay into brick and discharge them, and to push the plungers down to open the molds again to receive clay. The shaft G is borne by frames A² A³ and 20 bears a disk, G', on its end, which has a driving crank-arm, G². The pitman-lever H connects with crank G², so as to operate it as a pitman during its whole revolution and as a lever during a part of the same to give a compound 25 series of motions to the plungers to press and discharge the brick and to open the molds again for clay. The pitman-lever H connects with crank G² by a bearing-box, H', in its end, which is borne in a slotted seat in 30 which it is adjustable crosswise by set-screws, blocks, or otherwise, to adjust for wear of the several joints connecting with the plungers E F. The link-bar E³ connects with the other end of pitman-lever H by a pivot-pin, H², held 35 on each side of bar E³ by branches of the pitman-lever, and link-bars F³ connect with the pitman-lever by pivot-pin H³ at a point above pivot-pin H², as shown. The pitman-lever H has pivot-pins H⁴, with friction-rollers to run 40 upon guideways h on frames A' A² during a part of the movement, so as to give a lever motion to the pitman by the motion of the crank to produce varied compound motions of the plungers. The plungers are cored out 45 hollow to receive steam to heat them to prevent the clay from clogging onto their faces. The steam is introduced into one top plunger by flexible pipe or hose at Q, and is passed from one to the other and discharged from the 50 second by means of passages Q', cored or bored out at the sides, which open from the chambers from wells or depressions Q² at the bottom, so as to carry off the condensed water. The steam and water pass by reciprocating pipes 55 Q³, which telescope one in the other with a suitable packing, into the lower plungers, from which the water is drained away by a flexible hose or pipe. The filler-box C' is moved back and forth under the hopper C and over the 60 molds by link-bar P' from lever P. The lever P is pivoted to frame A² at P², and engages at P³ with a cam-channel cut around the face of disk G' next to frame A², so as to give the proper motions to the filler-box at the proper times in the series of motions of the machine. This cam is circular for three-fourths of the

revolution, so as to hold the filler stationary while the other parts act to press and push out the brick, and in the other fourth, approximately, the cam bends inward and out 70 again to move the filler forward and back again to fill the molds and return, pushing the brick forward at the first motion while the upper plungers are raised and the lower plungers descend to open the molds. 75

The machine is driven by a belt on wheel K' on shaft K, or otherwise. Shaft K has bearings in frames A² A³, and a wheel, K², loose thereon, with a friction-clutch apparatus, K³, to throw it into or out of motion while 80 wheel K' turns to drive the machine. Wheel K² turns wheel L' and wheel L² on shaft L, which has bearings in the same frames, and wheel L² turns wheel G⁴ on shaft G to operate the machine. The proportions of the wheels 85 in this train are arranged to reduce a rapid belt-motion to the speed proper for the making of the brick. The friction-clutch has a hollow coned part, M, forming one side of wheel K², and the wheel and part are held 90 loose on the shaft between collars k k' thereon. The solid coned part M' fits into the hollow of part M, and is loose on shaft K, but is turned by a pin from the shaft which works in a slot in part M', so as to let it be forced into or out 95 of part M to operate the machine by friction. The part M' is moved back and forth on the shaft to engage with part M by means of lever N', which connects with it by a yoke or collar in a channel around part M'. This lever has 100 bearings in slots in block N, which are cut obliquely in contrary directions on opposite sides, so as to act screw-like upon the lever to move it sidewise. 105

Fig. 1 shows the positions of the parts with the top plungers raised and the bottom plungers pushed down in the molds, and with the filler-box drawn forward over the molds, having pushed the brick forward onto table C' and filled the opened molds. From this position the disk G' turns, with its crank and pitman-lever H, in the direction of the arrow, so as to produce a series of different actions in a series of steps of time, as follows:

First. The filler-box is drawn back from 115 over the molds and remains stationary under the hopper C until the brick are pressed and discharged, and the back end of the pitman-lever H is raised and drawn back by crank G².

Second. This motion of the pitman-lever 120 raises bearing H⁴ from guideway h, and draws pivot-pin H² back in such a path as to push down the upper plungers into the molds, and moves pivot-pin H³ back in such a path as to let links F³ turn on their lower bearings 125 without moving the plungers until spurs F⁴ strike onto bearing a. The relations of the movements of the two pivots H² and H³ and of the two sets of plungers are promoted by the leverage between these pivots while the back 130 end of the pitman-lever is rising with the crank G², and the paths of the movements of the piv-

ots are controlled so as to move the upper plungers positively down against any tendency to stick fast, and so as to hold the lower plungers stationary, by a bar, R, which extends from pivot H^4 to pivot R' on the stationary frame, with which it engages by a slot, R^2 , so as to permit pivot H^4 to move up in a path (shown in dotted lines h^2 in Fig. 1) within a curve having a radius of the length 10 of this bar, which holds it as a swinging tie, while leaving it free to descend within it by the slot to follow guideway h .

Third. The motion of the crank carries the pitman, with its connected link-bars, backward, so as to bring the upper ends of the links 15 over the molds with all their pivot-pins and the plungers nearly into one line or plane, causing the two sets of plungers to be forced toward each other on the clay in the molds to 20 press it into brick, pushing down by link-bar E^3 on the upper plungers, and pulling up by links F^3 on the lower plungers, so the parts approach toward the positions shown in full lines in Fig. 2. During this movement the 25 lower plungers are forced to rise in the molds to make a portion of the compression from below by the action of spur F^4 on bearing a as a lever as the links F^3 turn backward. The pivot-pin H^2 is laid out as upon the square 30 corner of a right-angled triangle, with pivots H' and H^3 on the other corners. This is arranged to bring the pivot H^2 to the center or vertical point in advance of pivot H^3 , so that the maximum pressure does not occur at 35 the center, as it would do if the two pivots passed it at the same time.

Fourth. The motion of the crank carries the end of pitman H down, so as to produce a lever action thereof on the pivot-pins H^2 H^3 to 40 carry pin H^4 and the end of its link-bar onward most rapidly and counteract the tendency of the movement beyond the center or vertical to relieve the pressure. This lets the increase of pressure slack up somewhat for a 45 short period while the parts are carried to their farthest point backward, and the crank descends below the dead-center; but the lifting action of the lower plungers on the brick in the molds is continued by the lever action 50 of spur F^4 on bearing a until the backward motion of link-bar F^3 ceases. During the slackening of pressure the particles of clay in the molds still held under high pressure have time to flow together or coalesce solidly, and 55 the continuance of upward motion tends to break the first set of the particles to the walls of the molds, so that the final pressure can compact the whole brick uniformly to the center.

Fifth. As the lever motion continues it acts 60 to stop the backward travel of the lower pivot-pin, H^2 , and start it into return motion before pivot H^3 , to bring it into a position between that and the pivot in the top plunger-head, so that when both pivots H^2 H^3 move back by 65 the action of the crank on the pitman H they will approach the center or vertical point

more nearly in one line or plane with the pivots in the plunger-heads, and produce an additional increase of pressure to finish the compression of the brick. This step of motion 70 brings the several parts into the positions shown in full lines in Fig. 2, and brings down the pivot H^4 , with its friction roller, to contact with its guideway h .

Sixth. The crank carries the back end of 75 the pitman still farther down and forward, so that it turns as a lever on pivot-pin H^4 , which is carried forward in a path determined to suit the needs by the form and position of guideway h , so as to lift and push forward the 80 ends of the pitman-lever and its connected link-bars, so as to pull or push the brick up in the molds without lifting the top plungers from them until reaching the tops of the molds. This motion continues until the brick are 85 raised entirely out of the molds, the top plungers moving most rapidly to free the brick and give room for the filler-box to pass under them and brings the parts into the positions shown in dotted lines in Fig. 2. 90

Seventh. The crank carries the back end of the pitman-lever forward at the bottom of its course from the position shown in dotted lines in Fig. 2, so as to complete the lifting of the top plungers, and pushes the parts toward the 95 positions shown in full lines in Fig. 1. The disk G' , with its cam-channel, comes into action to move lever P , so as to push the filler-box C' forward and push the brick out of the way onto table C^4 , and to carry a supply of clay forward 100 over the molds. The movement of the pitman-lever carries the pivot H^4 to a position over the pivot of part T' . The upper plungers rise till the pin T^2 on plunger-head E' strikes cross part T^3 , which extends from upright bars T 105 on the two sides extending up from the adjustable part S , so as to stop and prevent further upward movement of the plungers.

Eighth. The crank carries the back end of the pitman-lever forward and upward, so as 110 to push all the parts into the positions shown in full lines in Fig. 1. The contact of part T^3 as a holder or tie with pin T^2 on the upper plunger-head holds that and causes the front end of pitman-lever H to swing forward and 115 downward as the pivot H^4 passes over and down the curve of part T' , so as to force the link-bar F^3 down and push the bottom plungers down in the molds to let the clay descend and fill them for a new set of brick. The depth 120 to which the bottom descends in the molds, and the consequent quantity of clay which the molds will receive to form the brick, is determined by a part, S , which is hinged to the bed-plate A or frame behind, and is raised and adjusted and held by a screw-bolt, S' , and securing-nut in front, so that the bottom of the lower plunger-head, F' , will descend to and rest upon part S . The front end of guideway h is formed of part T' , which is suitably curved 130 and adjustable on its pivot by means of tie-bars T , which are connected to one of these on

each side and held by part S, with which it moves up and down.

These eight steps of movement of the parts complete the actions required for each set or lot of brick, and bring the parts to the positions at which they were at the start, as shown in full lines in Fig. 1. The motions are repeated with suitable rapidity continuously, so as to form and discharge the brick on table 10 C⁴, from which they are removed by hand for hacking up or putting in kiln.

When it is desired to stop the machine, the lever N' is raised at its free end beside the operator, who removes the brick, and is fastened 15 in place in a notch or holder, which throws the clutch K³ out of gear with the wheel K², so as to let the machine stop.

The machine is easily started by pushing this lever down and holding it in place in a 20 like way, so as to force the revolving solid cone M' into the hollow cone of wheel K², to cause it to turn by friction.

The clutch is arranged to slip at any great increase of stress to avoid breaking any part.

25 The several parts are made and arranged and connected among themselves to produce the desired series of actions, and various modifications of parts can be made.

I claim—

30 1. A brick-machine formed with a driving-crank, G², bearing a pitman, H, provided with a lever-pivot, H⁴, and a camway-bearing, h, therefor, and having upper and lower plungers connected to pitman H at different points 35 by link-bars, and governed by spur F⁴ and tie R, adapted to produce from the motion of the crank a series of varied motions of the plungers, substantially as set forth.

2. In a brick-machine, the pitman H, provided with link-bar connections at different points from upper and lower plungers adapted to move the plungers toward each other at one time, and provided with pivot H⁴, adapted to move and act upon a guideway, h, to 45 produce a variable lever action of the pitman with its connected parts.

3. In a brick-machine, the pitman H, provided with link-bar connections at different points from upper and lower plungers, adapted to move the plungers toward each other at one time.

4. In a brick-machine, a pitman, H, provided with a link-bar connection, to which is attached a plunger for pressing brick, and 55 having a pivot, H⁴, adapted to move and act upon a guideway to produce a variable lever action of the pitman.

5. In a brick-machine, a pitman, H, provided with link-bar connection with one or 60 more plungers for pressing brick, and with a pivot, H⁴, adapted to move and turn upon a guideway to produce variable lever action and having a crosswise adjustable crank-connection adapted to adjust the leverage.

65 6. In a brick-machine, a pitman, H, provided with link-bar connections from differ-

ent parts to plungers adapted to act toward each other to press brick, and having a crosswise adjustable crank-connection adapted to adjust the leverage of the pitman between the 70 two sets of plunger-connections.

7. In a brick-machine, a pitman, H, provided with link-bar connections with one or more plungers adapted to press brick, and provided with a pivot, H⁴, adapted to move 75 and act along a guideway, in combination with a guideway having an adjustable portion, T'.

8. In a brick-machine, a pitman, H, provided with a link-bar connection with a 80 plunger adapted to press brick, and with a pivot, H⁴, adapted to move and act along a guideway, combined with a slotted holder, R; connecting the pitman with a holding-pivot, R'.

9. A pivoted holder, R, combined with a compression apparatus having a plunger, and adapted to pull down the plunger or to prevent it from failing to come down upon the material to be compressed.

90 10. In a brick-machine, the combination of upper and lower plungers and a pitman-lever having connections to the plungers, with a part, R, from the pitman pivoted to a fixed support and adapted to draw down the plungers into the mold.

11. In a brick-machine, a pitman, H, provided with a link-bar connection to a plunger adapted to press brick, combined with a holder, T³, adapted to engage with a part, T², connected with a support and adapted to control the action of the plunger during a portion of the travel of the pitman.

12. A sliding holder, T³, adapted to engage with a part, T², connected with a pressure-plunger, and adapted to pull down the plunger or to prevent it from failing to come down to open the mold to receive the clay.

13. In a brick-machine, the combination of upper and lower plungers and a pitman-lever having connections to the plungers, with a part, T², connected with a stationary support and adapted to come in contact with a part connected with the pitman to draw down the lower plungers in the mold.

14. In a brick-machine, a pitman, H, provided with a link-bar connection with a plunger adapted to press brick, which link-bar is provided with a side spur, F⁴, adapted to assist in moving the plunger.

15. In a brick-machine, a link-bar connection from a plunger adapted to press brick connected with a source of motion adapted to give it a sidewise or swinging motion at one end, and provided with a side spur, F⁴, and bearing therefor, adapted to act during a part of the motion to cause a lengthwise motion of the link-bar.

16. In a pressing-machine, a link-bar, F³, adapted to be moved sidewise at one end, 130 provided with a spur at one side adapted to cause lengthwise motion of the link-bar.

17. In a brick-machine, a friction-clutch, K³, provided with an operating-lever adapted to work as a lever pivoted around the driving-shaft, and engaged with bearings on each 5 side in parts having oblique slots cut in them adapted to move the lever and part of the clutch sidewise along the shaft by the turning of the lever.

18. The device for operating a friction-10 clutch provided with oblique slots cut in stationary parts to hold the ends of an operating-lever on opposite sides of the shaft, and adapted to move the lever and part of the clutch along the shaft by turning the lever.

19. A brick-machine plunger adapted to move downward into the mold to press a brick therein, provided with a chamber in the plunger adapted to receive steam for heating the plunger-face, and having an upward-20 opening passage from a well or depression in the bottom of the chamber adapted to discharge water therefrom by means of passing steam.

20. In a brick-machine, a system of pipes and 25 passages connected through a space within an

upper compression-plunger and by an upward passage from the bottom of such space, to a space within a lower plunger adapted for the circulation of steam to heat both plungers and to discharge water from the bottom of the space in the upper plunger, substantially as set forth. 30

21. In a brick-machine, a mold provided with a lower plunger having a link-bar connection from a source of power adapted to 35 push the plunger down to open the mold, combined with a separate part, S, under it, provided with a means of vertical adjustment adapted to determine the extent of the descent of the plunger to open the mold. 40

22. The combination of two plungers adapted to press on opposite sides of a brick or block with a pitman connected by link-bars directly with each plunger.

In testimony whereof I affix my signature in 45 the presence of two witnesses.

ALBERT D. THOMAS.
